UNITED STATES PATENT OFFICE.

WILLIAM H. POWELL, OF EAST ORANGE, NEW JERSEY, ASSIGNOR TO CROCKER-WHEELER COMPANY, OF AMPERE, NEW JERSEY, A CORPORATION OF NEW JERSEY.

ELECTRIC SWITCH.

SPECIFICATION forming part of Letters Patent No. 783,981, dated February 28, 1905.

Application filed October 24, 1904. Serial No. 229,741.

To all whom it may concern:

Be it known that I, WILLIAM H. POWELL, a citizen of the United States of America, and a resident of East Orange, county of Essex, State of New Jersey, have invented certain new and useful Improvements in Electric Switches, of which the following is a specification.

This switch has been devised for the rheostatic control and reversal of electric motors, and is particularly applicable in conditions where it is desired to run the motor in either direction and to provide a considerable number of control-points, the two classes of control being effected by the operation of a unitary rotatable member preferably of the drum type, upon which suitable contacts are mounted and brought into contact with contact-fingers ranged along the side of the drum. In switches of this character, particularly when they operate a rheostatic control, as many contact-fingers are required as there are control positions for effecting the rheostat connections in addition to the fingers for the reverser-contacts and the fingers for effecting multiple breaks in the circuit in passing to the off position. With separate contact-rings on the controller-drum for each finger, a drum and switch of excessive length is required, particularly if there are a considerable number of control positions.

The object of this invention is to avoid such excessive length of switch by placing the contact-fingers for the control positions in two rows ranged along diametrically opposite elements of the drum, and so disposing contacts on the drum that contact will be made with all of the fingers in the same order by movement of the drum in either direction from a middle off position.

In the accompanying sheets of drawings, which form a part of this application, Figure 1 is an elevation of a switch embodying my invention. Fig. 2 is a section on the line II-II of Fig. 1. Fig. 3 is a development of the switch-cylinder, together with a diagram of the connections, showing the arrangement for motor regulation by rheostatic variation of the armature-current. Fig. 4 is a develop-

ment of a modified arrangement of contacts and connections for a shunt-motor with regulation also by variation of the field strength.

The switch, as illustrated, comprises a rotatable member in the form of a drum D and two rows of contact-fingers. One of the rows has fingers L, R' to R¹, A, and S arranged to contact along an element of the drum, and the other row has fingers R, R² to R¹⁴, and AA arranged to contact along an element of the drum diametrically opposite to the element along which the first row is contacting at the same time. The contacts on the drum and the fingers co-operating with them may be classified according to use into three groups for multiple breaking, rheostatic control, and reversal. The first group has contacts l and r, which contact with the fingers L and R, and thereby connect one end of a series of resistances r' to r¹³ to the line. The purpose of this ring of contacts and fingers is to introduce two additional breaks in the circuit and cut off the resistance from the line L when the switch is brought to the off position in which it is illustrated. The second group has contacts k' to k¹⁴, which contact with the fingers R' to R¹⁴, leading from the resistance and connects in or cuts out the sections of the resistance, as required, at the different control positions 1 to 14 of the switch. The third group has contacts a, aa, s, and s', which contact with the fingers A, AA, S, and S' to effect reversal in the circuit connections through the armature when the switch is thrown from one side to the other of the off position. The contact a is in electrical connection with the contacts k' to k¹⁴ of the second group through the bases on which these contacts are supported and attached to the core. The contacts aa, s, and s' are likewise connected.

The contacts for the rheostatic control are placed on the controller-drum along two spiral lines, half in each spiral, one spiral with the contacts k' to k⁷ being right-hand and the other spiral with the contacts k⁸ to k¹⁴ being left-hand. These spirals and the contacts composing them are symmetrically disposed on the drum with respect to the element a,

which is the element that lies opposite one of the rows of fingers, L, R' to R'', A, and S, when the controller is at the off position and represents the off position of the switch-drum with respect to this row of fingers. It also follows that the spirals and the contacts composing them are symmetrically disposed with respect to the diametrically opposite element o' o' of the drum, and as this lies opposite the other row of fingers, R, R'' to R'''', and AA, when the controller is in the off position, this element represents the off position of switch-drum, with respect to this second row of fingers.

The drum-contacts are so placed that they will make contact with the contact-fingers in proper sequence and that the sequence shall be the same for either direction of movement from the off position. In order that this may be possible with two fingers and two contacts on each ring of the drum, the fingers which belong to the same group must each be so placed that the finger with which contact is last made, as R'''', is opposite the finger with which contact is first made, as R', and the finger with which contact is made next to last, as R''', is opposite the finger with which contact is made second, as R'', so that if the fingers in one row are in sequence from top to bottom the fingers in the other row will be in reverse sequence. As the purpose of the contacts in the application illustrated is to short-circuit additional sections of resistance as the switch is turned toward a full running position, the leading edge of each contact has to be positioned just over the element of the drum at which contact is to be made; but owing to the duplicate use of the contact in making connections the opposite edge of each contact becomes the leading edge to be properly positioned on operating the switch toward the reverse running position. The width of each of the contacts is therefore determined by the distance apart of the leading edges and this in turn is regulated by the departure from symmetry of the controller positions 1 and 14, at which contact is made with the first and last contact-fingers of the group. If position 14 were the same angular distance from the element o' o' that position 1 is from the element o o, so that the two would be in symmetry, then each contact would have to be narrow enough to lie across but one positional element of the drum. This is insufficient, and in order that the contacts may be wider the circle is so subdivided that the position 14 will be at a greater angular distance from the element o' o' than the angular distance between position 1 and the element o o, with position 14, which is the end position for one direction of movement coinciding with position 2 for the contrary direction of movement. As illustrated, the two end positions at which contact is made with the group of armature rheostat-fingers are out of symmetry with each other by the angular space of consecu-

tive positions and under these conditions each contact will lie across two positional elements.

As the contacts in either group, as k' to k'', effect controller changes at different angular positions of the drum from the angular positions at which controller changes are effected by any of the contacts of the other group of contacts, k'' to k''', it follows that the angular distances of the contacts k' to k'' from the contact-fingers R' to R'' are different from the angular distances of the contact-fingers k'' to k''' from the contact-fingers R'' to R''', and this is true not only when the switch is in the off position, but also when the switch is in any operative position, since operation of the switch to any position adds to or subtracts from all the angles to an equal extent and does not disturb their inequality.

In the modified arrangement of Fig. 4 it is not necessary to have the first and last actual controller positions 1 and 13 out of symmetry in order to give sufficient width or length to the contacts k' to k'', since these contacts are brought into and out of contact at positions 1 to 8, these being the end positions with respect to the contact-fingers of this group, and since they are five divisions out of symmetry these contacts are extended over the spaces between five positions. This modified arrangement also illustrates an arrangement of fingers and contacts for control by variation of the field strength between positions 8 and 13, in which the fingers F' to F'' and contacts j' to j''' are likewise grouped in two rows in accordance with my invention. The purpose of these contacts is reversely to those of the other group and is to cut in resistance into a circuit as the switch is moved toward the full-running position. Hence the leaving edge of each contact has to be positioned just back of the element of the drum at which additional resistance is to be cut in, and that there may be sufficient length to each contact advantage is taken of the fact that the end positions at which this group is used are out of symmetry reversely to the end positions for the other group.

It will be seen that the positions of the contacts as above defined in reality apply to substantially the positions of the advancing or leaving edges accordingly as the controller changes are effected at either of the above edges.

What I claim as new, and desire to secure by Letters Patent of the United States, is—

1. In an electric controlling-switch, a rotatable member, two sets of contacts carried thereby and symmetrically disposed with respect to a plane through the axis of the rotatable member, and two sets of contact-fingers disposed on opposite sides of the rotatable member, each contact-finger lying in the path of a contact in each set of symmetrically-disposed contacts on the rotatable member, and each of the symmetrically-disposed contacts

- having a path of movement past a contact-finger in each set of contact-fingers, the relative positions of the contacts and contact-fingers being such that the angular distances from 5 one set of contacts to one set of contact-fingers will be different from the angular distances of the other set of contacts from the other set of contact-fingers at any angular position of the switch, substantially as described.
- 10 2. In an electric controlling-switch, a rotatable switch-cylinder, two sets of contacts carried thereby and symmetrically disposed with respect to a plane through the axis of the cylinder, and two sets of contact-fingers disposed 15 on opposite sides of the cylinder, each contact-finger lying in the path of a contact in each set of symmetrically-disposed contacts on the cylinder, and each of the symmetrically-disposed contacts having a path of movement 20 past a contact-finger in each set of contact-fingers, the relative positions of the contacts and contact-fingers being such that the angular distances from one set of contacts to one set of contact-fingers will be different from the 25 angular distances of the other set of contacts from the other set of contact-fingers at any angular position of the switch, substantially as described.
3. In an electric controlling and reversing

switch a rotatable member, contacts for effecting a reversal of electrical connections carried thereby, two sets of contacts carried thereby and symmetrically disposed with respect to a plane through the axis of the rotatable member, contact-fingers coöperating with the contacts for effecting reversal, and two sets of contact-fingers disposed on diametrically opposite sides of the rotatable member, each contact-finger lying in the path of a contact in each set of symmetrically-disposed contacts 30 on the rotatable member, and each of the symmetrically-disposed contacts having a path of movement past a contact-finger in each set of contact-fingers, the relative positions of the contacts and contact-fingers being such that 35 the angular distances from one set of contacts to one set of contact-fingers will be different from the angular distances of the other set of contacts from the other set of contact-fingers at any angular position of the switch, substantially as described.

Signed by me at East Orange, New Jersey, this 22d day of October, 1904.

WILLIAM H. POWELL.
